UNITED STATES PATENT OFFICE.

BRUCE B. STONE, OF MOUNT CLARE, WEST VIRGINIA.

ACETYLENE-LAMP.

1,091,982.

Specification of Letters Patent. Patented Mar. 31, 1914.

Application filed February 27, 1913. Serial No. 751,123.

To all whom it may concern:

Be it known that I, BRUCE B. STONE, a citizen of the United States, residing at Mount Clare, in the county of Harrison and 5 State of West Virginia, have invented a new and useful Acetylene-Lamp, of which the following is a specification.

This invention relates to acetylene generators and more particularly to miners' acetylene lamps.

An object of the present invention is to provide an acetylene gas lamp with two independent gas generating chambers adapted to supply acetylene gas to two independent 15 burners.

Another object is to provide an improved valve construction for the regulation of the water supply to the gas generating chambers which will prevent any clogging of the 20 water supply tube and will provide means whereby the latter may be readily cleaned.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within 30 the scope of what is claimed without departing from the spirit of the invention.

In the drawings accompanying this specification and forming a part thereof, the preferable form of my invention is illustrated in 35 which:

Figure 1 is a plan view of my improved acetylene lamp. Fig. 2 is a cross sectional view thereof, taken on the line A—A of Fig. 1. Fig. 3 is a view in elevation thereof. 40 Fig. 4 is a sectional view taken on the line B—B of Fig. 3.

Referring to the drawings in which similar reference numerals designate corresponding parts throughout the several views, 1 is 45 a water reservoir or tank provided with an inlet opening 2 at the top thereof. The said opening is provided with a cover or lid 3 therefor, which lid is provided with a centrally disposed air inlet opening 3' which 50 allows the water in the tank 1 to pass readily through the openings in the bottom thereof.

The cover 3 is hingedly mounted at 4 and is preferably provided with a spring snap of the usual construction, the same not being 55 illustrated.

Rigidly supported below the reservoir 1 are the downwardly extending cylindrical

supports 5, there being two of these supports as illustrated in Fig. 2. These supports threadedly engage as at 7, the carbide containers 6, these containers being cup-like in shape and are provided with an annular rib or shoulder 8 against which the lower end of the support 5 abuts and form a gas-tight juncture therewith. The upper extremity 9 of the container is spaced a distance from the bottom of the water reservoir 10 and forms therebetween what are designated as non-communicating gas chambers 20 and 21. Located approximately central of the supports 5 are the openings 11 in the bottom plate of the water reservoir 1 in which openings are disposed the water outlet tubes 12 which are provided with the enlarged heads 13 which are secured within the openings 11 of the plate 10, it being understood in this connection that each head portion 13 and the tube 12 may be forced into engagement with the side walls of the opening 11 or may be held in liquid-tight relation therewith by any suitable means. The head portion 13 is provided with a conical valve seat having an opening 14 therein which is adapted to fit the valve plunger or valve member 15. This member 15 is rigidly supported by a valve rod 16 which rod extends downwardly through the tube 12 and beyond the end thereof. It also extends upwardly through the water reservoir 1 and terminates in the thumb screw 17. The thumb screw 17 extends through the upper wall of the water reservoir 1 and threadedly engages a reinforcing boss 18 secured thereto. The upper terminal of the thumb screw 17 is provided with the outwardly flared head 19 which has a knurled face so that the latter may be readily engaged and easily turned for the adjustment of the valve 14—15, which valve it will be apparent controls the supply of water from the reservoir 1 to the carbide containers 6. From the foregoing it will be apparent that each carbide container or gas generator is provided with a separate and independent valve, and valve actuating mechanism which therefore renders each gas generator independent of the other.

Communicating with and extending for a slight distance within the gas chambers 20 and 21 are the gas outlet tubes 22 and 23 which it is to be noted are slit along their upper surface for the portion thereof which lies within the said gas chambers and the slit ends of these tubes are unrolled so as to be in the form of upwardly extending

troughs substantially as illustrated in Figs. 2 and 4, the object of these flared and mutilated ends being to prevent any of the water from spattering up therein and clogging the 5 gas outlet tubes. The gas outlet tubes 22 and 23 communicate with the gas burners 24 and 25 respectively which are located substantially centrally of a disk or reflector 26 which is suitably mounted upon the reservoir 10 1 to which it is secured in a rigid manner. In order to provide convenient securing means, a hook 27 is illustrated as being attached to the rear portion of the lamp and is adapted to fit within a suitable opening 15 provided in a miner's hat or may serve as a handle should it be the desire of the user to carry the lamp.

In the practical operation of my improved lamp, a certain amount of carbid is placed 20 within each of the carbid containers or cups and one of the valve rods suitably turned in order to admit water to the carbid containers. In this manner, gas will be generated and will be burned at the burner. When it 25 becomes apparent that the supply of carbid in one of the containers is about exhausted, the other valve is opened and the burner communicating therewith is lighted. In this manner both burners may be maintained in a lighted condition until one is 30 completely exhausted, at which time the cup or carbid container may be removed without the disturbing of the other container and the lamp will therefore remain lighted 35 and in a serviceable condition. By the peculiar construction of the valves as illustrated, the valve rods and valve may be withdrawn and the tubes 12 will thereby be maintained in an open position, it being 40 understood in this connection that the clogging of these tubes is a serious objection to the usual form of carbid lamps. Furthermore by the flaring and upturning of the 45 ends of the gas tubes, the danger of the latter becoming clogged by the spattering of the watered carbid is effectually prevented and the lamp will thereby remain in a serviceable condition.

The advantages accruing from the herein 50 described construction are important ones and combined to form an extremely useful and efficient acetylene miner's lamp.

What I claim is:—

1. In an acetylene lamp the combination 55 of a water reservoir provided with an inlet opening therein, a plurality of carbid containers removably mounted therebeneath and supported thereby, tubes communicating with the said reservoir and with the said 60 containers, means for regulating the water supply through the said tubes, gas burner tubes communicating with the said carbid containers and provided with flared ends.

2. In an acetylene lamp the combination of a water reservoir, cylindrical supports arranged therebeneath, cylindrical carbid containing cups threadedly engaging said supports, said carbid containers spaced a distance below said reservoir to form non-communicating gas chambers thereby, means 70 for supplying water from said reservoir to said containers, means for regulating the said supply, independent gas burner tubes communicating with the said gas chambers and terminating therein in shielded flared 75 upturned side portions.

3. In an acetylene lamp the combination of a water reservoir, provided with an inlet opening in the top thereof, a cover therefor and provided with an air inlet opening 80 therein, two cylindrical supports mounted beneath said reservoir and secured thereto, cylindrical carbid container cups threadedly engaging said supports, means for supplying water from said reservoir to said carbid 85 containing cups, means for regulating the supply, said cylindrical supports defining non-communicating compartments, independent gas burner tubes with gas burners at the outer extremities thereof, the inner 90 ends of said gas burner tubes extending within the said gas chambers and provided with shielded flared end portions.

4. In an acetylene lamp the combination of a water reservoir, carbid containing cups 95 removably mounted therebeneath and supported thereby, said carbid containers defining non-communicating compartments, gas burners mounted there in front, and gas burner tubes communicating with said gas burners and extending within said gas chambers and provided with shielded end portions.

5. In an acetylene lamp the combination of a water reservoir with an inlet opening 105 in the top thereof, two cylindrical supports mounted beneath the said reservoir and secured thereto, cylindrical carbid containing cups threadedly engaging said supports, means for supplying water from said reservoir to said carbid containing cups, means for controlling the said supply, a reflector supported by said reservoir, gas burners mounted there in front, gas supplying tubes communicating with the said burners and 110 extending within the said cylindrical supports, the end portions of said gas supplying tubes flared to provide shielded end portions.

In testimony that I claim the foregoing 120 as my own, I have hereto affixed my signature in the presence of two witnesses.

BRUCE B. STONE.
